(No Model.)

A. HOFMANN.

HARNESS.

No. 361,874.

Patented Apr. 26, 1887.

UNITED STATES PATENT OFFICE.

ADAM HOFMANN, OF INDIANAPOLIS, INDIANA.

HARNESS.

SPECIFICATION forming part of Letters Patent No. 361,874, dated April 26, 1887.

Application filed February 7, 1887. Serial No. 226,813. (No model.)

To all whom it may concern:

Be it known that I, ADAM HOFMANN, a citizen of the United States, residing at Indianapolis, in the county of Marion and State 5 of Indiana, have invented a new and useful Improvement in Harness, of which the following is a specification.

My invention relates to an improved harness for attaching draft-animals to carriages.

10 The object of my improvement is to quickly connect the harness when on the animal with the carriage.

The accompanying drawings illustrate my invention.

15 Figure 1 is a side elevation. Fig. 2 is a plan. Fig. 3 is a section through *a a*, Fig. 2. Fig. 4 is a side elevation of the shaft-coupling.

A represents the saddle, B the back-band, C the hame, D the breeching, and E the girth, 20 of an ordinary single harness.

F is a metallic plate having a hook, G, and four loops, *h*, *i*, *j*, and *k*. The back-band B is secured to loop *h*, the breeching-strap *l* is secured to loop *i*, the girth E is secured to loop 25 *j*, and loop *k* is connected with the hame by a strap, *s*.

H is a flat plate having a slot, *m*, and secured to the inside of the shaft I by clips *n n*.

J is a plate having an eye, *o*, and a loop, *p*, 30 and it is mounted on plate H so as to slide along the slot. The trace L is secured at one end to the loop *p* on plate J, and at the other end to the single-tree *r*, and remains always with the shaft.

35 The operation is as follows: It will be un-

derstood that there are two of each of the plates F, H, and J to each harness, one on each side, the plates F being secured to the back-band or saddle, as before described, and the plates H and J being secured to the shafts 40 opposite the saddle. The shafts are raised, and the horse wearing the saddle, plates F, and the other usual parts of the harness is brought into position beneath the shafts. The shafts are then lowered until the eyes *o* of the 45 plates J engage the hooks G of the plates F, where they are retained by the light flat spring *t*. The horse is thus instantly and securely attached to the carriage. As the horse moves forward and the single-tree swings with 50 his step, plates J slide longitudinally forward and back on the plates H. It is obvious that the hook G may be transferred from plate F to plate J and the eye *o* from plate J to plate F without departing from the spirit of my invention. 55

I claim as my invention—

In a harness, the combination, with the back-band, the girth, the hames, the breeching-strap, the trace, and the carriage-shaft, of 60 the plate F, having hooks G and loops *h*, *i*, *j*, and *k*, the slotted plate H, secured to the shaft, and plate J, having eye *o* and loop *p*, all arranged to co-operate substantially as and for the purpose specified.

ADAM HOFMANN.
